UNITED STATES PATENT OFFICE

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed October 9, 1929. Serial No. 398,309.

My invention relates to railway traffic controlling apparatus, and particularly to apparatus of the type involving train-carried governing mechanism controlled by energy received from the trackway. More particularly my present invention relates to the trackway portion of such apparatus, and is especially suitable for train control systems of the coded continuous inductive type.

10 One feature of my invention is the provision of novel and improved means for controlling the application of coded train governing current to the track rails in advance of a train.

15 I will describe one form of apparatus embodying my invention, and will then point out the novel features thereof in claims.

The accompanying drawing is a diagrammatic view showing one form of apparatus embodying my invention.

20 Referring to the drawing, the reference characters 1 and 1^a designate the track rails of a stretch of railway track along which traffic normally moves in the direction indicated by the arrow. These rails are divided by insulated joints 2 to form a plurality of sections, of which only one complete section A—B, is shown in the drawing. Each section is provided with a track circuit comprising a track relay designated by the reference character T with an exponent corresponding to the location. The source of track circuit current for each section is a transformer 9, the secondary of which is connected 25 across the track rails and the primary of which is supplied with current in the manner hereinafter explained.

25 Each track section is also provided with a line relay L, a line repeating relay L^R, and a code relay V. Each line repeating relay L^R is controlled by a front contact 8 of the associated line relay L, so that the repeating relay is energized or de-energized according as the line relay is energized or de-energized. The 30 circuit for the repeating relay L^R will be obvious from the drawing without explanation.

35 Line relay L at location A is provided with a circuit which passes from one terminal of a battery B¹², through front contact 5 of re-

peating relay L^R, front contact 3 of track relay T^B, winding of relay L, front contact 10 of track relay T^A, winding of relay V, front contact 4 of track relay T^B, and front contact 6 of relay L^R to the other terminal of battery B¹². The contacts 5 and 6 of the repeater relay L^R constitute a pole-changer, whereby the polarity of the current supplied to relay L is normal or reverse according as relay L^R is energized or de-energized. The parts of this circuit are so proportioned and adjusted that when the circuit is closed relay L will be energized but the code relay V will be de-energized, that is, the back point of its contact 7 will be closed. Track circuit current will then be supplied to the primary of transformer 9 from terminals X and Y, which terminals are connected with a suitable source of alternating track circuit current.

40 When a train enters section A—B, it will, of course, de-energize track relay T^A, so that the front point of contact 10 of this relay will open and the back point of the same contact will close. This will cut the line relay L out of the circuit, and will close a shunt across the circuit, which shunt includes a battery B⁶. This battery will then assist or oppose battery B¹² according as line repeater relay L^R is closed or open, but in either event, the code relay V will become closed. If the two batteries oppose each other, relay V will close because of the reduced resistance of the circuit due to the exclusion of the line relay L. The desired result may conveniently be accomplished by making battery B¹² a 12-volt battery, and making battery B⁶ a 6-volt battery. When relay V becomes closed, the source of track circuit current will be disconnected from the primary of transformer 9, and train governing current will be applied to this primary by a suitable means which forms no part of my present invention. The apparatus controlled by the code relay V may, for example, be similar to the apparatus shown in my co-pending application, Serial No. 171,767, filed March 1, 1927, for railway traffic controlling apparatus.

45 The circuit for the line relay L and the code relay V is provided with a second shunt,

which includes the back point of contact 4 of track T^B. It follows that when the section to the right of point B is occupied, so that track relay T^B is de-energized, line relay L will be de-energized, but code relay V will become energized if a second train enters section A—B, because battery B^v will then be connected directly with the code relay V. To put the matter in another way, when a train enters section A—B, thereby closing the first shunt for the line relay circuit, code relay V will become energized regardless of whether track relay T^B is energized or de-energized.

The line relays L and the line repeater relays L^R will ordinarily control wayside signals and also the train governing current, but these features form no part of my present invention, and, consequently, they are omitted from the drawing for the purpose of simplicity.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track divided into sections; a track relay, a line relay, and a code relay for each section; a circuit for the line relay of one section including a front contact of the associated track relay and a front contact of the track relay for the next section in advance as well as the winding of the code relay for the associated section, a source of current of relatively high voltage, means for supplying current of normal or reverse polarity from said source to said circuit according as the line relay for the said section in advance is energized or de-energized, a shunt around said line relay and said front contact of the first track relay which shunt includes a back contact of said first track relay and a source of current of relatively low voltage, and a shunt around said first source of current and the pole-changing contacts and the front contact of the second track relay which shunt includes a back contact of said second track relay, the parts being so proportioned and adjusted that said code relay is normally open but is closed when said first shunt is closed whether said second shunt is closed or open.

2. In combination, a stretch of railway track divided into sections; a track relay, a line relay, and a code relay for each section; a circuit for the line relay of one section including a front contact of the associated track relay and a front contact of the track relay for the next section in advance as well as the winding of the code relay for the associated section, means for supplying current

of normal or reverse polarity at relatively high voltage to said circuit according as the line relay for the said section in advance is energized or de-energized, means operating when said first track relay is open to close a shunt across said circuit including a source of current of relatively low voltage, and means operating when said second track relay is open to close a second shunt across said circuit, the parts being so proportioned and adjusted that said code relay is normally open but is closed when said first shunt is closed whether said second shunt is closed or open.

3. In combination, a stretch of railway track divided into sections, a track relay and a line relay as well as a code relay for each section, a circuit for the line relay for one section controlled by the track relay for the same section and the track relay for the next section in advance and including the associated code relay and a source of current, means operating when said first track relay is open to close a shunt across said circuit including a second source of current, and means operating when said second track relay is open to close a second shunt across said circuit, the parts being so proportioned and adjusted that said code relay is normally open but is closed when said first shunt is closed whether said second shunt is closed or open.

In testimony whereof I affix my signature,
ROBERT M. GILSON.
